UNITED STATES PATENT OFFICE.

LORENZ ADALBERT ENZINGER, OF WORMS, HESSE, GERMANY.

FILTER-PRESS.

SPECIFICATION forming part of Letters Patent No. 393,633, dated November 27, 1888.

Application filed June 30, 1887. Serial No. 243,017. (No model.) Patented in England April 25, 1887, No. 5,982; in Germany April 26, 1887, No. 42,894; in France April 29, 1887, No. 183,195; in Belgium April 29, 1887, No. 77,263; in Sweden May 3, 1887, No. 988; in Italy May 18, 1887, XLIII, 112; in Norway May 20, 1887, No. 538; in Spain July 13, 1887, No. 11,153; in Austria-Hungary November 6, 1887, No. 19,090 and No. 44,748, and in Luxembourg February 2, 1888, No. 955.

To all whom it may concern:

Be it known that I, LORENZ ADALBERT ENZINGER, a subject of the Grand Duke of Hesse, and residing at Worms, in the Grand Duchy of Hesse, Germany, have invented new and useful Improvements in Filter-Presses, (for which Letters Patent have been granted to me in the following countries, to wit: Great Britain, April 25, 1887, No. 5,982; Germany, April 26, 1887, No. 42,894; France, April 29, 1887, No. 183,195; Beigium, April 29, 1887, No. 77,263; Sweden, May 3, 1887, No. 988; Italy, May 18, 1887, No. 112, Volume XLIII; Norway May 20, 1887, No. 538; Spain, July 13, 1887, No. 11,153; Austria-Hungary, November 6, 1887, respectively numbered 19,090 and 44,748, and Luxembourg, February 2, 1888, No. 955,) whereof the following is a specification.

My invention relates to filter-presses or filtering apparatuses composed of a number of juxtaposed frames and of filtering-walls placed between the same; and its object is to provide more efficient means than heretofore employed in like apparatuses for allowing the air contained in the frames or entering therewith into the liquid to be filtered to escape, and whereby air may be caused to pass into the frames, when at the end of an operation the remaining liquid is drawn off. For this purpose the frames and the filtering-walls are inserted between two chambers located at the ends of the apparatus, and they are provided with four holes each—two at the top and two at the bottom—the said holes forming, when the parts are put together, four channels. One of the lower channels and one of the upper ones communicate with the interior space of the alternate frames and with the chamber designed to receive turbid liquor, so that while the liquor flows through the lower channel into the frames the air passes through the upper channel from the frames to the said chamber. The other two channels communicate with the remaining frames and with the chamber for filtered liquor, and they serve, respectively, to conduct filtered liquor and air from these frames to the said chamber. Both chambers are provided with cocks for the outlet of the air collecting therein.

On the annexed two sheets of drawings an apparatus involving my improvements is represented by Figure 1 in perspective view, the frames and the filtering-walls being separated from each other a certain distance and only a limited number thereof being shown. Figs. 2 and 3 are respectively a front view and a vertical section on line 1 2 of one of the frames, and Fig. 4 is a perspective view of a composite filtering-wall arranged to be employed in the improved filter press.

In Fig. 1, Q is the chamber into which the turbid liquor is introduced by the cock e. M M are two of the frames for turbid liquor, one of which is also shown by Figs. 2 and 3. O O O are three frames, and R is the chamber for filtered liquor, the latter having the discharge cock p. T are the filtering-walls, which consist of sheets of filtering paper or cloth. The frames M and O are provided inside with vertical bars, forming a grate for supporting the filtering sheets or walls. In all the frames and in the filtering-sheets there are four holes—two at the bottom and two at the top—which, when the parts are pressed together, form four channels—the two lower ones, a b, and the two upper ones, c d. Moreover, the chamber Q has two orifices, i and m, registering, respectively, with the channels b and c, whereas the chamber R has the orifices k and n, (shown in dotted lines,) which are opposite to the ends of the channels a and d. In each of the frames M the hole forming part of the channel b communicates by a slit, t, and the hole forming part of the channel c by a slit, l, with a passage, t, running along at the ends of the grate-bars, and consequently with the spaces between the bars, (see especially Figs. 2 and 3,) so that the turbid liquor introduced into the chamber Q will pass from the same through the channel b to the frames M, and that the air will escape from the latter to the chamber Q through the channel c. In a like manner the inner space of each of the end frames, O, is put in communication by a slit, o, with the channel a, and by a slit, r, with the channel d, for allowing the filtered liquor to pass from all the frames O through the channel a and the air through the channel d.

to the chamber R. The slits o and r are exactly analogous to the slits l and t. (Shown in Figs. 2 and 3.) The frames O are also analogous to the frame M, the former, however, being turned end for end when placed in the press, so as to bring the slits o and r in communication with the channels a and d, respectively, while the slits l t of the latter communicate with the channels c h.

In order that the air may escape freely through the channels c and d, the frames M and O require to be made of such form that the bubbles of air rising within the liquor will pass to the slits l and r. For this purpose it is advantageous to make the frames, the filtering-walls, and the chambers Q and R of square form, and to arrange them with their diagonals in vertical and horizontal position, as shown by the drawings. Under these conditions the frames, the filtering-walls, and the chambers may be supported by and shifted from one side to the other upon and between four bars, C, connecting together the standards A of the apparatus. The said frames, walls, and chambers are pressed together by means of the head-plates K and the screw J with hand-wheel W. On the chambers Q and R are mounted the glass cylinders f, in which the air coming from the frames M and O collects, so that the quantity thereof present can always be observed.

h h' are the cocks by which the air is blown off, u u' drain-cocks, and g g pressure-gages. If the apparatus is to be put into operation, the filtering battery, composed of the frames, the walls, and the chambers, is tightened up, as stated, and the cocks h h', u u', and p are closed. Turbid liquor is then admitted by the cock e to the chamber Q, while at the same time the cock h is slowly opened until the liquor has risen in the glass f, the said cock being thereupon closed. During this operation the liquor runs through the orifice i and the channel b into the frames M and displaces the air, which passes through the slits l and the channel c into the upper part of the chamber Q. The cock h' of the chamber R being then slowly opened, the liquor passes from the frames M through the neighboring filtering walls or sheets T on both sides thereof, and arrives in purified state in the frames O, whence it runs through the slits o and the channel a to the chamber R, while the air present in the said frames escapes by the slits r, the channel

d, the chamber R, and the cock h'. The course 55 of the liquor and the air is indicated in the drawings by arrows. When the filtration is finished, all spaces filled with turbid liquor may be emptied by the cock u, those containing the filtrated liquor by the cock u', the cocks 60 h and h' being at the same time opened for the induction of air. Thus all losses of liquor otherwise apt to occur at the end of an operation are avoided.

In case the filtering material consists of 65 sheets of paper, which are apt to be torn when there is a pressure of a liquid on one side and air or gas on the other, such sheets, when applied in the described apparatus, are secure against rupture, as with ordinary care no accumulation of air or gas adapted to endanger the paper will occur in the frames of the apparatus. 70

The filtering-walls T, consisting of sheets of paper or cloth, may be replaced by other walls—such, for instance, as those shown by Fig. 4—which consists each of a frame, N, closed 75 on both sides by sheets P of wire-gauze faced at the edges with inder-rubber frames P', the said frame N being provided with an orifice, q, to be closed by a screw plug for filling it 80 with cellulose or other suitable filtering material.

I claim as my invention—

In a filter-press, the combination, with each other, of a number of frames, M, for turbid liquor, a number of frames, O, for filtered liquor alternating with the former, filtering-walls interposed between the frames M and O, and two chambers, Q and R, arranged at the ends of the apparatus, the frames M and O and the 90 filtering-walls having each two holes at the bottom and two at the top, which, when the said parts are put together, form the two lower channels, a b, and the two upper ones, c d, the channels b and c communicating with the inner space of the frames M and the chamber Q, while the channels a and d communicate with the inner space of the frames O and the chamber R, substantially as and for the purpose 95 specified.

In testimony whereof I have hereunto set my hand in the presence of two subscribing witnesses.

LORENZ ADALBERT ENZINGER.
